UNITED STATES PATENT OFFICE.

WILLIAM HARLOW TAYLOR, OF TEMPLE, TEXAS.

COTTON-CHOPPER.

SPECIFICATION forming part of Letters Patent No. 593,002, dated November 2, 1897.

Application filed December 17, 1896. Serial No. 616,084. (No model.)

To all whom it may concern:

Be it known that I, WILLIAM HARLOW TAYLOR, a citizen of the United States, residing at Temple, in the county of Bell and State of Texas, have invented a new and useful Cotton-Chopper, of which the following is a specification.

My invention relates to cotton-choppers, and has for its object to provide a simple and efficient device of this class whereby grass, weeds, and the like may be removed from the spaces between stands of cotton, corn, and similar vegetation.

Further objects and advantages of this invention will appear in the following description, and the novel features thereof will be particularly pointed out in the appended claims.

In the drawings, Figure 1 is a plan view of a machine constructed in accordance with my invention. Fig. 2 is a central longitudinal section of the same. Fig. 3 is a rear view showing in dotted lines the positions of the members of the hoe-frame when partly elevated. Fig. 4 is a plan view showing a reversed arrangement of the draft and operating devices. Fig. 5 is a detail view of one of the crank-hangers detached. Fig. 6 is a similar view of the locking device whereby the parts are held in position to prevent communication of motion from the ground-wheel to the chopper mechanism. Fig. 7 is a detail view of one of the chopper-blades and securing-plates detached, said blade and securing-plate being shown in side elevation and section. Fig. 8 is a detail view of one of the hoe-frame bars detached. Fig. 9 is a detail view in section of the direction or guide pulley for the operating-chain. Fig. 10 is a detail view of the standard detached. Fig. 11 is a detail view of a modified form of standard.

Similar numerals of reference indicate corresponding parts in all the figures of the drawings.

The main transverse beam or axle 1 is preferably constructed of flanged iron, and to it are bolted the laterally-bent contiguous extremities of the side bars 2, connected by a transverse bar 3, thus forming a substantially rectangular frame which is braced longitudinally by tie-rods 4, preferably constructed in the form of bolts and extending through reg-

istering perforations, respectively, in the main beam 1 and cross-bar 3. The hounds preferably consist of a metal frame 5, to which 55 is attached the rear end of a tongue 6, carrying a suitable whiffletree, as in the ordinary practice, the extremities and intermediate arch 7 of said hounds being secured to the main frame by means of the above-described 60 tie-rods 4 and contiguous bolts 8, by which the extremities of the side bars 2 are secured, a central bolt 9 engaging the arch. In Figs. 1 and 2 this hound-frame is shown attached to the main beam; but it is adapted also to 65 be attached to the cross-bar 3 by the same means as those above described, as shown in Fig. 4, thus adapting the machine to be reversed when it is desirable by reason of a preference of the operator to have the supporting or ground wheels 10 located at the rear 70 rather than at the front of the main frame.

Mounted terminally in the transverse members of the main frame are the spindle portions of parallel longitudinal crank-hangers 75 11, which support a vertically-adjustable hoe-frame consisting of downwardly-convergent side bars 12. The lower extremities of these side bars are connected by a longitudinal hoe-shaft 13, and the upper extremities of said 80 bars, which are attached to the crank-hangers, are preferably arranged vertically and are provided with means whereby the bars may be adjusted to vary the elevation of their lower extremities or of the hoe-shaft 13. The 85 means illustrated in the drawings for accomplishing this vertical adjustment of the hoe-frame consist of a plurality of half-bearings 14, formed, respectively, in fixed and movable sections 12^a and 12^b of the upper extremities of 90 the side bars 12, the movable section being preferably pivoted, as at 15, to the fixed section and being held in its normal position by means of a bolt 17, engaging registering openings in the contiguous extremities of the fixed 95 and movable sections.

It will be seen that either of the sets of half-bearings may be engaged with the reduced journals 18 of the crank-hangers. The front and rear side bars 12 of the hoe-frame are 100 connected in pairs by longitudinal tension-braces 18^a and yielding flexible connections 19, having inserted spring-sections connecting the front bars 12 with a suitable hanger

20, depending from the tongue. The attachment of the rear ends of these flexible connections or yielding braces 19 to the side bars 12 consist of eyebolts 21, which when the 5 draft apparatus is reversed, as described in connection with Fig. 4, may be engaged with corresponding openings 21^a, a plurality of openings being provided upon each side bar to agree with the vertical adjustment of the side 10 bars by the means heretofore described and consisting of the registering half-bearings 14. The openings 21^a in the side bars, which in any adjustment of the mechanism are at the 15 rear of the frame, are utilized for the attachment of the foot- rests 22, and located over the same is a seat 23, having supporting-arms 24, which are reversible in a manner 20 similar to the other parts of the mechanism to arrange the seat contiguous either to the cross-bar 3, as shown in Figs. 1 and 2, or to the transverse beam 1, as shown in Fig. 4.

The hoe-shaft is provided at an intermediate point with a fixed plate 25, to which the 25 hoe-stem 26, carrying the hoe or chopper blades 27, is attached, the connection between the extremities of the stem and the blades preferably consisting of securing-plates 28, to one extremity of each of which is pivoted a blade, while the other extremity carries a securing-bolt 29, engaging a slot 30 in the blade. These blades are curved, and the curvature corresponds with that of similar portions of the surface of a cylinder of which the hoe-shaft is the axis, and each blade is inclined to the 30 axis of motion or to the hoe-shaft, whereby one end thereof engages the soil in advance of the other. Furthermore, the terminal edges of each blade are inclined to the length of the blade or to the side edges thereof, 35 said terminal edges being preferably arranged approximately at right angles to each other, whereby the lower or engaging extremity of a blade is sharpened to a point to facilitate its entrance into the soil. Obviously when the 40 draft mechanism is arranged, as shown in Figs. 1 and 2, contiguous to the main beam 1 the rear edges of the blades will be depressed to first enter the soil, and a reversal of the draft mechanism must be accompanied by a 45 corresponding reversal of the hoe-stem to secure a proper operation of the hoe-blades, said stem being detachably secured to the shaft.

Various means may be employed for communicating motion to the hoe-shaft, but in the drawings I have shown a driven shaft 30^a, connected by gears 31 and 32 to one of the ground-wheels 10, said driving-shaft being mounted in the sliding frame or carrier 33, 55 consisting of side arms 33^a, connected by a transverse brace 34 and mounted to slide on one of the tie-rods 4. The gear 31, which is mounted upon this carrier, is adapted to be arranged in engagement with either of a plurality of gear-faces 32^a and 32^b on the gear 32, a spring 35 being employed to move the carrier inwardly or into engagement with the

inner gear-face when released. Attached to the carrier is a locking device consisting of a handle 36, carrying a pawl 37 to engage either of a series of notches in the rack 38, whereby the carrier may be locked with the gear 31 in engagement with either face of the gear 32, or out of engagement, to prevent the communication of motion from the ground-wheels to the hoe-shaft.

The driven shaft 30 is connected by gearing with the hoe-shaft 13, in the construction illustrated, by means of chain-wheels 39 and 40 and a chain 41, the upper side of the latter traversing a direction or guide pulley 42, mounted upon one of the crank-hangers 11, between contiguous shoulders or collars 43, said pulley being split to facilitate its application to the crank-hanger and having its sections held in place by means of transverse pins or rivets 44, as shown in Fig. 9.

It is desirable, in going to and from a field in which the machine is to be operated, to elevate the choppers or hoe-blades to avoid contact with obstructions in the road, and in order to enable this to be accomplished with facility, and at the same time adapt the hoe-shaft to be moved laterally to enable the operator to maintain it accurately in line with the row of plants being cultivated, I attach operating-levers 45 to the squared extremities of the crank-hangers, providing each lever with a locking device—such, for instance, as a pawl 46—for engaging a segment 47.

It is obvious that when both handles are swung to the right the hoe-shaft will be moved a corresponding distance to the left, and vice versa, thus enabling the operator to follow with accuracy any irregularities in the rows of plants and cause the hoes to operate with precision, and when it is desired to elevate the hoes it may be accomplished by swinging both of the levers outward, as indicated by the dotted lines in Fig. 3. This figure shows the hoe-frame elevated only a portion of the distance of which it is capable. The motion of the levers may be continued until they reach a vertical position opposite to that normally occupied thereby, when the hoe-blades will be at such a height from the ground as to avoid meeting obstructions.

In order to support the portion of the frame remote from the transverse beam, I preferably employ standards 48, having round spindle portions 49, extending through suitable openings in the contiguous portions of the side bars 2 and locked in the desired positions by means of nuts 50. Obviously when the draft mechanism is reversed to the position shown in Fig. 4 the runner portions 51 of the standards are reversed to extend rearwardly.

In Fig. 11 I have shown a slightly-modified form of standard wherein a colter or supporting-wheel is employed.

The double-gear which I employ for communicating motion to the mechanism enables me to drive the latter at different speeds, as it is desirable to have increased speed of the

hoe-shaft in cutting grass and weeds between stands of cotton.

Various changes in the form, proportion, and the minor details of construction may be resorted to without departing from the spirit or sacrificing any of the advantages of this invention.

Having described my invention, what I claim is—

- 10 1. In a cotton-chopper, the combination with a supporting-frame, of a folding hoe-frame having pivotally-connected side bars, crank-hangers supporting the side bars, and means for turning the hangers to elevate the side bars, a hoe-shaft mounted in the hoe-frame, and means for communicating rotary motion to the shaft, substantially as specified.
- 15 2. In a cotton-chopper, the combination with a supporting-frame, of a folding hoe-frame having downwardly-convergent side bars pivotally connected at their lower extremities, crank-hangers upon which the upper extremities of the side bars are fulcrumed, means for turning the crank-hangers to elevate the side bars, a hoe-shaft mounted coaxially with the pivotal point of connection of the lower extremity of the side bars, and means for communicating rotary motion to the hoe-shaft, substantially as specified.
- 20 3. In a cotton-chopper, the combination with a supporting-frame, of a folding hoe-frame having downwardly-convergent side bars pivotally connected at their lower extremities, crank-hangers mounted in the supporting-frame and having the upper extremities of the side bars of the hoe-frame fulcrumed thereon, means for varying the vertical adjustment of the side bars with relation to the crank-hangers, means for turning the crank-hangers to fold and elevate the hoe-frame, a hoe-shaft supported by the hoe-frame, and means for communicating rotary motion to the hoe-shaft, substantially as specified.
- 25 4. In a cotton-chopper, the combination with a supporting-frame, of parallel crank-hangers, side bars fulcrumed contiguous to their upper ends upon the crank-hangers, and having downwardly-convergent portions pivotally connected together at their lower extremities, said side bars being provided with fixed and movable sections provided with registering half-bearings to engage the journal portions of the crank-hangers, and means for securing the movable section in its operative position, a hoe-shaft mounted upon the hoe-frame, and means for communicating rotary motion to the hoe-shaft, substantially as specified.
- 30 5. In a cotton-chopper, the combination with a supporting-frame, of a folding hoe-frame having crank-hangers, side bars fulcrumed upon the crank-hangers and provided with downwardly-convergent portions pivotally connected at their lower extremities, a hoe-shaft mounted upon the hoe-frame, means

for communicating rotary motion to the hoe-shaft, levers attached to the extremities of the crank-hangers, and means for securing said levers in their adjusted positions, substantially as specified.

6. In a cotton-chopper, the combination with a supporting-frame, of a hoe-frame having crank-hangers mounted for lateral swinging movement, means for varying the lateral position of the hoe-frame by the angular adjustment of the hangers, locking devices for the same, a hoe-shaft mounted upon the hoe-frame, and means for communicating rotary motion to said shaft, substantially as specified.

7. In a cotton-chopper, the combination with a supporting-frame, of a hoe-shaft and means for communicating rotary motion thereto, and hoe-blades carried by stems attached to the hoe-shaft and arranged angularly with relation to said shaft, said blades being provided with terminal diagonal divergent edges, substantially as specified.

8. In a cotton-chopper, the combination with a supporting-frame, of a hoe-shaft and means for communicating rotary motion thereto, hoe-stems carried by the shaft and provided with terminal transversely-disposed securing-plates, hoe-blades pivotally mounted at the extremities of the hoe-stems upon said plates, and means for securing said blades at the desired angular adjustment, substantially as specified.

9. In a cotton-chopper, the combination with a main frame having a transverse beam bearing ground-wheels, side bars, and a cross-bar parallel with the said beam, tie-rods connecting said transverse bar and beam, a hoe-frame supported by the main frame, a carrier mounted to slide upon the main frame, a hoe-shaft, a driven shaft operatively geared with the hoe-shaft, said driven shaft being provided with a gear to mesh with a gear on a contiguous ground-wheel, yielding means for normally holding said carrier in its operative position, and a locking device for holding the carrier in its inoperative position against the tension of said spring, substantially as specified.

10. In a cotton-chopper, the combination of a main frame having a transverse beam, side bars, and a connecting cross-bar, tie-rods connecting said cross-bar and beam, a hoe-frame mounted within the main frame and carrying chopping mechanism, standards arranged contiguous to the extremities of the cross-bar, and draft mechanism and means for attaching the same interchangeably to the beam and cross-bar, substantially as specified.

In testimony that I claim the foregoing as my own I have hereto affixed my signature in the presence of two witnesses.

WILLIAM HARLOW TAYLOR.
